DESIGN FOR AN AUTOMOBILE

Armin C. Frank, Milwaukee, Wis.

Application October 28, 1942, Serial No. 108,626

Term of patent 14 years

To all whom it may concern:

Be it known that I, Armin C. Frank, a citizen of the United States and resident of Milwaukee, in the county of Milwaukee and State of Wisconsin, have invented a new, original, and ornamental Design for an Automobile, of which the following is a specification, reference being had to the accompanying drawing, forming part thereof.

I claim:

The ornamental design for an automobile, as shown.

ARMIN C. FRANK.
